UNITED STATES PATENT OFFICE.

JASON SAMUEL MCCANTS, OF TALLADEGA, ALABAMA.

DITCHING-PLOW.

SPECIFICATION forming part of Letters Patent No. 749,082, dated January 5, 1904.

Application filed July 10, 1903. Serial No. 165,018. (No model.)

To all whom it may concern:

Be it known that I, JASON SAMUEL MCCANTS, a citizen of the United States, residing at Talladega, in the county of Talladega and State 5 of Alabama, have invented a new and useful Ditching-Plow, of which the following is a specification.

This invention relates to plows, and especially to that class of plows which are used 10 for ditching and terracing. It has for its object to provide a plow of this class which shall be simple in construction, easily manipulated, effective in operation, and means by which a ditch may be cut and the dirt thrown out of 15 the same in a simple and convenient manner, as will hereinafter appear.

With these and other ends in view my invention consists in the combination, with a single beam or standard, of two separate plows, 20 a right-hand and a left-hand one, which are capable of being used independently of each other, the arrangement being such that one of said plows shall be adapted to cut a ditch or furrow. At the end of such ditch or furrow 25 the ditching-plow is thrown out of operation and the other plow, which I call a "scoop-plow," is thrown into operation, the said scoop-plow throwing the loose dirt on the return trip in the same direction as the 30 furrow slice has been turned on the first trip of the plow. By again reversing the plows and repeating the operation additional dirt may be loosened and thrown out of the furrow until a ditch of the desired depth has 35 been formed.

My invention further consists in the improved construction, arrangement, and combination of parts, all tending toward providing a plow of the class described which shall 40 possess superior advantages in point of simplicity, durability, and general efficiency, as will be hereinafter fully described, and particularly pointed out in the claims.

In the accompanying drawings I have 45 shown a simple and preferred form of embodiment of my invention; but I desire it to be understood that I do not thereby limit myself to the precise structural details shown, but reserve the right to such changes and 50 modifications as may be resorted to within the scope of my invention and without de-

parting from the spirit or sacrificing the efficiency of the same.

In said drawings, Figure 1 is a perspective view of my improved plow, showing one of 55 the plow members elevated. Fig. 2 is a longitudinal sectional view of the device. Fig. 3 is a transverse vertical sectional view taken on the line 3 3 in Fig. 2. Fig. 4 is a front elevation.

Corresponding parts in the several figures are indicated by similar numerals of reference.

1 designates a beam, which may be of wood or metal and which is provided on the sides 65 thereof with laterally-extending segmental flanges 2 2. Firmly secured to the under side of said beam and in alignment with the flanges 2 2 is a standard 3, having a head 4, which is extended forwardly and rearwardly, as well 70 as laterally, to enable it to be secured firmly to the beam and also to place the head thereof in alignment with the flanges 2. When the beam is constructed of metal, it may within 75 the scope of my invention be formed integrally with the standard 3. The latter is provided below the head thereof with recesses 5, and the portion of the standard including said recesses is transversely perforated for the pivotal attachment by means of a bolt 6 80 of a pair of brackets 7, carrying the plows 8 and 8^a. Said plows are of ordinary construction and differ from each other only in this respect, that the plow 8 is an ordinary ditching-plow, while the plow 8^a has its moldboard 85 extended to form a scoop, whereby the dirt engaged by said scoop shall be thrown in an upward and outward direction. Both moldboards are provided with points 9 9^a, and they are in most respects of any well-known 90 or suitable construction, they being provided at their inner adjacent sides with landsides 10 and 10^a, which, as well as the moldboards, are suitably secured to the respective brackets, which are pivotally connected with the 95 standard of the plow.

The handles 11 of the plow are secured to the rear end of the beam, the upper ends of said handles diverging in an upward direction and being spaced in the usual manner, 100 as by means of a rung 12 and a brace 13. The lower ends of said handles are made to con-

verge downwardly and are securely attached to opposite sides of the plow-standard 3, at the lower end of the latter, by means of a transverse bolt 14. The space between the converging lower ends of the handles forms a slot 15, in which is mounted a slide 16, the sides of which are provided with recesses 17 to accommodate the lower ends of the handles with which the said slide is thus connected. The lower portion of the slide 16 is provided with spaced ears 18, between which is mounted a roller 19. The slide 16 is also provided with an upwardly and rearwardly extending handle 20, which extends upwardly below and between the plow-handles 11. The rear end of the beam 1 is provided with a guide-bolt 21, which extends through a slot 22 in the handle 20, thus limiting the movement of the latter and of the head 17, carrying the roller 19. The handle 20 is capable of being secured at any desired adjustment by means of a hook 23, adapted to engage any one of a plurality of eyes 24 upon the upper side of the beam.

25 Pivotedly connected to the opposite sides of the beam 1 in rear of the standard 3 are a pair of levers 25, the lower ends of which are connected by links 26 with the inner sides of the brackets 7, upon which the plows are mounted. The links 26, as shown in the drawings hereto annexed, are in the form of bell-cranks, their pivotal points of attachment, however, being not at their angles, but at the ends of their respective arms. The object of 30 the peculiar shape, therefore, is not to cause the said links to operate as bell-crank levers, but merely to cause them to conform to the shape of the parts or members which are connected thereby and to enable them to operate freely and in the most advantageous manner. In the construction of my improved plow it will be found practical to use differently-shaped links, and I regard connecting-links of any shape and configuration as being 35 within the scope of my invention. Hooks 29 are provided, said hooks being connected with the beam and adapted to engage eyes 30 upon the levers 25 for the purpose of maintaining the latter in adjusted position.

40 The brackets 7 are provided with upwardly-extending segmentally-slotted guide-straps 27, engaging guide-lugs 28 upon the sides of the beam. These guide-straps are conformed to engage the upper sides of the segmental flanges 2 upon the sides of the beam, as will be readily understood by reference to the drawings, and these straps are not only for the purpose of guiding the plows in the desired direction when thrown upwardly and 45 out of operation, but also to strengthen and reinforce the related parts. In order to retain the levers 25 and their related parts at any desired point of adjustment, said levers are provided with suitably-spaced eyes 28', 50 adapted to be engaged by hooks 29, which are connected with the upper side of the

beam 1 a short distance in rear of the fulcrum of said levers.

The operation and advantages of this invention will be readily understood from the foregoing description, taken in connection with the accompanying drawings.

The two plow members may when desired be used in connection with each other, and my improved plow will thus answer the practical purpose of a lister by throwing the dirt simultaneously to both sides. For ditching purposes the scoop-plow 8^a may by manipulating the proper lever be raised to an upright position, where it will not engage the soil, and the ditching-plow 8 will then operate alone to turn a furrow slice. At the end of the furrow the position of the plows is reversed, the plow member 8^a being thrown into active operation, while the member 8 is raised out of operation. The entire plow being then turned, the plow member 8^a will engage the bottom of the furrow and throw in the direction of the furrow slice all the soil which has been loosened by the operation of the furrow plow. By repeating this operation as frequently as may be desired a ditch of any desired depth within the capacity of the device may be cut. While the plow members 8 and 8^a are being reversed, the slide 16, carrying the roller 19, may be lowered until the weight of the plow is supported thereon. The plow members 8 and 8^a may thus be readily manipulated without any additional weight or burden being thrown upon the operator.

For terracing or hillside work the operation of the plow will be readily understood by those skilled in the art to which the invention appertains. It will also be seen that when the plow is to be transported along the roads or from one field to another it is not necessary to drag or to haul it upon a wagon, but simply to lower the slide carrying the roller 19, when by raising the plows slightly from the ground the said roller will carry the weight and enable the implement to be conveniently carried to the desired point.

Having thus described my invention, I claim—

1. A plow - beam, a standard extending downwardly from the same, brackets connected pivotally with opposite sides of said standard, and plow members carried by said brackets.

2. A plow - beam, a standard extending downwardly from the same and having oppositely-disposed segmental flanges, brackets connected pivotally with said flanges, and right and left hand plow members carried by said brackets.

3. A plow - beam, a standard extending downwardly from the same, and a plow member having a bracket pivotally connected with said standard near the upper end of the latter.

4. A plow - beam, a standard extending downwardly from the latter, a plow member,

a bracket supporting said plow member and having pivotal connection with the standard, an operating-lever connected pivotally with the beam, and a link connecting said lever with the pivoted plow-supporting bracket.

5 5. A plow-beam, a standard extending downwardly from the same, right and left hand plow members, brackets supporting said plow members and having pivotal connection with the standard, levers connected pivotally with the beam, links connecting said levers with the plow-supporting brackets, and means for retaining said levers in adjusted position.

10 6. A plow-beam, segmental flanges upon opposite sides of said beam, a standard extending downwardly from said beam, brack-

ets connected pivotally with said standard, right and left hand plow members supported upon said standards, means for effecting adjustment of the latter, segmental braces connected with the plow-supporting guide-lugs, engaging the segmental flanges upon the plow-beam and having segmental slots, and guide-lugs upon the sides of the plow-beam engaging the segmental slots in said braces.

15 In testimony that I claim the foregoing as my own I have hereto affixed my signature in the presence of two witnesses.

JASON SAMUEL McCANTS.
